UNITED STATES PATENT OFFICE.

MARIUS MATHIESEN, OF CHICAGO, ILLINOIS, ASSIGNOR TO MATHIESEN SANDBERG COMPANY, OF CHICAGO, ILLINOIS, A CORPORATION OF ILLINOIS.

COLLAPSIBLE LOOP AERIAL.

Application filed August 1, 1925. Serial No. 47,562.

My invention relates to improvements in loop aerials for use in connection with radio apparatus, and has special reference to loop aerials which are collapsible into a minimum space for storage and transportation.

The object of my invention is to improve and simplify the manufacture of such devices, to provide simple means whereby the turns of the loop can be readily wound on the frame with less than the final tension required and whereby the frame can be easily extended and the turns properly tensioned when the device is completed.

A further object of my invention is to produce a multiple turn loop of the kind mentioned having a tap or third connecting wire, connected to substantially the middle of the aerial wire and accomplishing this latter in a very simple manner.

Further features and objects of my invention will appear hereinafter.

My invention will be more readily understood by reference to the accompanying drawings forming part of this specification and in which:

Figure 1, is a side elevation of a collapsible loop aerial constructed in accordance with my invention;

Figure 2, is a fragmentary, vertical sectional view on the line 2—2 of Fig. 1;

Figure 3, is a fragmentary, vertical sectional view on the line 3—3 of Fig. 2;

Figure 4, is a fragmentary vertical sectional view on the line 4—4 of Fig. 1; and

Figure 5, is a horizontal sectional view on the line 5—5 of Fig. 1.

In said drawings 1 represents a mast which consists of a lower tubular section 2 and an upper part 3 which is telescopically mounted in the lower part to slide up and down. The upper part or section 3 of the mast 1 is shown in Fig. 1, as in its extended position and it is adapted when the loop is collapsed to slide down into the lower section 2. The mast is adapted to be positioned vertically for use and is adapted to be mounted on a base 4, an upstanding rigid spindle 5 being provided on the base 4 adapted to enter the lower end of the mast. The mast, or in other words the whole loop can be turned on the spindle 5 to best position the aerial for reception.

At the upper end of the part 3, I provide a rigid cross bar 6 and I provide a similar cross bar 7 at the lower end of the part 2.

To complete the frame of the loop I provide laterally extending frame arms 8 arranged to be extended out in opposite directions from the middle portion of the mast and provided on their outer ends with rigid cross arms 9.

The several cross arms are notched to receive the turns of the aerial wire 10 which is wound on the arms in a plurality of turns.

In the form of frame illustrated the wire 10 is wound on the arms 6, 7 and 9 in the form of a flat spiral extending in a single layer from end to end of the cross bars except as to some details of winding by which I am enabled to join a third wire or tap 11 to substantially the center or middle portion of the aerial.

In the construction of many radio sets it is desirable to connect the loop aerial to the receiving apparatus not only at each end but also at the middle thereof.

In winding such a loop as that shown it has proved to be a difficult matter to make the winding symmetrical and be able to bring the middle portion of the winding at the base of the mast in convenient position for making a tap.

It is not practicable to make a tap other than at the base of the mast and in forms of winding heretofore used it has not been possible to make the center tap between an equal number of turns on each side of the mast as the total number of turns with an equal number of notches on each side of each arm results in the usual straight winding in an odd number of complete turns. With an odd number of complete turns the ends of the aerial wire being mounted on the lower cross-bar 7 the middle of the wire is at the top cross arm 6 and it is impracticable to connect the third wire to the aerial wire at the top cross arm.

By means of my invention I am enabled to provide an equal number of the turns on each side of the mast in the form illustrated six of these turns are thus shown on each side of the mast. Each of the cross arms 6, 7 and 9 are provided with six notches 13 in the outer edge of each end of the arm except the lower arm 7 which is provided with seven of these notches in each end as best shown in Fig. 4.

As best shown in Figs. 4 and 5, I begin winding the aerial wire 10 at one end of the cross bar 7 at preferably the left hand end

of the bar as shown in Fig. 4. The beginning end 14 of the wire 10 is secured to the left hand end of the lower crossbar by a suitable binding post 15 to which is also secured 5 the flexible connecting wire 16.

The laterally extending arms 8 of the frame are hingedly mounted at their inner ends to a short section 17 of tubing slidingly mounted on the upper part 3 of the mast 10 and adapted to permit the part 3 to slide through same as the mast is collapsed and extended. The normal position of the tubular support 17, when the frame is extended is in contact with the upper end of the lower 15 part 2 of the mast as shown in full lines in Fig. 1, but during the process of winding the aerial wire 10 on the frame this tubular connection 17 is slid up on the mast a short distance thus drawing in the cross arms 9 20 slightly. This is to permit the winding on of the aerial wire under less than the final desired tension.

After the loop is completed the several 25 turns are properly tensioned by sliding the tubular connection down into contact with the lower part 2 thus forcing the arms 9 outwardly and enlarging the frame to that extent.

The wire 10 is preferably wound on the 30 arms in a clockwise direction beginning with the end 14. The opposite end of the first turn enters the second notch 18 in the arm 7, and likewise each successive turn advances 35 into the next successive notch in the arm until the last or sixth turn 19 advances into the seventh notch 20. Instead of carrying 40 the wire directly around the frame I provide an auxiliary notch 21 and as best shown in Fig. 5, I carry the wire 10 back through this notch and across the mast as shown at 45 22 and then I start to wind the wire 10 on the opposite ends of the cross arms beginning with the inner notch 23 and ending with the seventh notch 24 thus providing 50 six complete turns on each side of the frame, the wire 10 ending at the binding post 28 on the lower cross bar 7.

I make a connection to the part 22 by soldering thereto a connecting clip 25 and clamping its outer or free end beneath a binding post 26 mounted on a block of insulation material 27 secured to the tubular part 2 of the mast. The flexible connecting wire 11 is adapted to be secured in the binding post 26. By this means I am enabled 55 to make a tap or connection to the exact middle point of the loop wire and make such connection at the bottom of the mast.

The mast being made of two pieces 2 and 60 3 one of which slides within the other I provide latch means for retaining the mast extended. Such means comprises a spring 65 pressed stop or bolt 29 carried by the upper part 3 of the mast and adapted to have its outer end 30, which is tapered, projected

out through an opening 31 in the wall of the lower tubular part 2 of the mast. The bolt 29 and hole 31 are adapted to register when the mast is fully extended. By forcing the bolt back through the opening 31 the mast 70 can be collapsed. In drawing the part 3 of the mast out to extend the frame the tubular support 17 is drawn up above its normal position in contact with the upper end of the lower part of the mast and consequently 75 the arms 8 are not fully extended at this time. This relation of the parts permits the mast to be fully extended without the necessity of applying any considerable force. In other words, there is practically no hindrance to the easy extension of the mast. After the mast is extended the support 17 can be readily pushed down into contact with the upper end of the lower part 2 of the mast the two arms 8 and the support 17 80 to which they are hinged at 32 acting at this time as a powerful toggle lever to enlarge 85 the frame and tension the turns of the wire 10. It should be understood that the several turns are fixed in the notches by some suitable means such as a drop of glue at each 90 point of contact.

As many modifications of the invention will readily suggest themselves to one skilled in the art I do not limit or confine my invention to the specific details of construction herein shown and described.

I do not herein claim the movable arm carrying member on the mast for tensioning and loosening the turns of wire, such forming the subject-matter of my co-pending application, S. N. 11,213, filed February 24, 1925.

I claim:—

1. In a collapsible loop aerial, having a mast and arms projecting from the mast in a single plane, cross arms on the mast and its arms and forming a frame, an aerial wire having its two ends on the same cross arm and wound around the frame in an even number of turns progressing regularly across the cross-arms from turn to turn, one half of the turns being on each side of the mast the wire crossing over from the last turn on one side to the first turn on the other side at the cross arm carrying the two ends of the wire, and a tap wire connected to the aerial wire at said cross over portion.

2. In a collapsible loop aerial, a mast, arms adapted to be extended at opposite sides of the mast to form a frame, cross arms on the mast and the cross arms, all of the arms having wire receiving openings at their outer edges for receiving the turns of an aerial wire, an aerial wire wound in the openings beginning at one side and wound in the same direction clear across, the ends of the aerial wire being secured to the cross arm at the base of the mast, said last mentioned cross arm having an auxil-

iary notch in one end adjacent to the mast through which the aerial wire can be carried back after the innermost turn at one end so that the innermost turn of the other end can 5 be started in the right direction to continue the winding in the same direction.

3. In a collapsible loop aerial, a mast, arms adapted to be extended at opposite sides of the mast, to form a frame, cross 10 arms on the mast and the arms, all of the arms having wire receiving openings at their outer edges for receiving the turns of an aerial wire, the openings in the two ends of the arms being equal in number, an aerial 15 wire wound in the openings beginning at one side and wound in the same direction

clear across, the ends of the aerial wire being secured to the cross arm at the base of the mast, said last mentioned cross arm having an auxiliary notch in one end adjacent to the mast through which the aerial wire can be carried back after the innermost turn at one end so that the innermost turn of the other end can be started in the right direction to continue the winding in the 20 same direction, and a tap wire connected to substantially the middle point of the aerial wire. 25

In testimony whereof, I have hereunto set my hand, this 18th day of July, 1925.

MARIUS MATHIESEN.
